UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed February 2, 1925. Serial No. 6,171.

To all whom it may concern:

Be it known that I, DAVID S. KENNEDY, a citizen of the United States, residing at Brooklyn, in the county of Kings and State of New York, have invented certain new and useful Improvements in Typographical Distributing Machines, of which the following is a specification.

This invention relates to typographical distributing machines, such as linotype machines of the general organization represented in U. S. Letters Patent to O. Mergenthaler, No. 436,532, wherein circulating matrices, are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through a distributing mechanism to the magazine from which they started. In some machines, such as the commercial model 9, where matrices may be drawn from several magazines and mixed together in the same line, the distributing mechanism includes a primary distributor which first sorts the matrices according to font, and a plurality of main distributors which sort the matrices of the individual fonts according to character and restore them to their proper channels in the magazines. With this type of distributing mechanism, the matrices, after font separation, pass down chutes or tubes and enter so-called lower distributor boxes, from which they are fed one at a time to the main distributors under the control of reciprocating pawls or escapements. In order that these pawls or escapements may cooperate properly with the matrices, the latter are provided in their bottom edges with central notches, which necessarily vary in shape and depth according to the thickness of the individual matrices. Besides adding to the cost of production, such notches in the matrices materially limit the space ordinarily required for the regular font notches, and

moreover, seriously weaken the matrices, especially when the latter are formed with other necessary cuts or notches. Furthermore, matrices comprising fonts used on other machines, such as those of the single distributor class, are excluded from use on machines of the multiple distributor class described, since they do not have the required central notches.

The present invention is intended to obviate the foregoing difficulties and contemplates certain improvements whereby the distributing mechanism may receive and handle matrices of all fonts whether they have or have not the objectionable central notches referred to. To this end, specifically, each of the lower distributor boxes is provided with shoulders to arrest the matrices at an inclination within the same and with a reciprocating finger to lift them at such inclination successively above said shoulders, so that the force of gravity may be utilized to permit the escape of the released matrices, one at a time, into position to be picked up by the distributor screws, the box also being provided with short inclined surfaces down which the matrices slide to the pick-up position and with overlying fingers to cooperate with the lifted matrices to aid them in assuming an upright position in descending the inclined surfaces.

In the accompanying drawings, the invention has been shown merely in preferred form and by way of example and as applied to the specific type of distributing mechanism indicated. However, many changes and variations may be made therein and in its mode of application, which will still be comprised within its spirit. It is to be understood, therefore, that the invention is not limited to any specific form or embodiment except so far as such limitations are specified in the claims.

In the drawings:

Fig. 1 is a side elevation of a lower distributor box constructed in accordance with this invention, certain parts being broken away to show the interior construction;

Fig. 2 is a vertical transverse section, taken on line 2—2 of Fig. 1;

Fig. 3 is a side elevation of the improved box, with the side plate removed, showing a matrix lifted above the arresting shoulders; and

Fig. 4 is a view similar to Fig. 3, showing the different positions a matrix assumes during its escape to the pick-up position.

10 The matrices X are released by the primary distributor (not shown) and enter one or another of the lower distributor boxes A, wherein they are guided and sustained by their projecting ears α upon upper and lower inclined rails A¹, A². Each box is associated with a distributor, which comprises the usual longitudinally ribbed bar B and the set of matrix conveying screws B¹, the arrangement being such that, as the 15 matrices escape from the box to the pick-up position, they will be immediately advanced by the screws across the horizontal rail extensions A³ into engagement with the bar B and thence along the same until finally released above their respective magazine channels. The foregoing parts and their mode of operation, except as hereinafter pointed out, are or may be of any approved 20 construction or as embodied in the commercial model 9 linotype.

According to the present invention, each lower distributor box A is provided with an escapement mechanism which serves the purpose of properly controlling the delivery 25 of matrices one at a time to the distributor screws, whether the matrices have or have not the special notches referred to. As shown in Fig. 1, matrices passing from the chute G are straightened up in the usual 30 way at X¹ so that their projecting ears α will properly engage the upper and lower guide rails A¹, A², down which the matrices slide by gravity until stopped by the engagement of their projecting ears with 35 shoulders A⁴ formed on the upper rails A¹ and corresponding shoulders A⁵ formed on the lower rails A². As shown, the shoulders A⁴ of the upper rails are disposed in such 40 relation to the shoulders A⁵ of the lower rails that a matrix will be arrested, as intended, at a forward inclination and slightly in advance of the pick-up ends B³ of the screw threads. A lifting finger C, mounted to reciprocate within the box and 45 actuated through the usual connections from a cam or eccentric stud B⁴ on one of the screws B, is employed to lift the matrices successively above the arresting shoulders A⁴, A⁵, so as to permit their escape by 50 gravity down short inclined surfaces A⁶ formed on the guide rails and leading to the pick-up position. The finger C is spring-controlled and arranged to lift an arrested matrix in its own plane, being 55 guided by a transverse pin C² so that its

purchase on the bottom edge of said matrix will be maintained throughout its upward stroke. It is pointed out that by arresting a matrix at an inclination, such as that indicated, its upper projecting ears will pass by gravity over the shoulders A⁴ when it is lifted (see Fig. 3) and thus be in position to descend the inclined surfaces A⁶ when the lifting finger recedes. These inclined surfaces extend from the tops of the 60 arresting shoulders to the rail extensions A³ and hence direct the escaping matrix into position to be picked up by the leading ends B³ of the conveying screws. With this arrangement, through the proximity of 65 the arresting shoulders to the receiving ends of the screws and the consequent short space an escaping matrix travels to the pick-up position, the timing of its delivery may be accurately determined and the screws set 70 accordingly. Moreover, any piling up of the matrices within the box will not interfere with their proper distribution since the lifting finger acts to release the matrices, one at a time only, in feeding them to the 75 screws. In this connection it may be noted that the screws are recessed or cut away at their receiving ends, as at B⁴, to give a released matrix more room and time to reach the pick-up position before it is engaged 80 by the leading ends B³ of the screw-threads.

It is desirable that an escaping matrix enter the screws in an upright or vertical position so that both the upper and lower ears α will be engaged at the same time by 85 the leading or pick-up ends B³ of the screw-threads. Accordingly, there is provided a pair of fingers A⁷ fastened on opposite sides of the box casing and arranged to cooperate with the upper projecting ears of a lifted 90 matrix and aid it in assuming an upright position preparatory to its escape to the screws. The matrix is thus not only prevented from tilting too far forwardly as 95 its ears rise clear of the shoulders A⁴, but it is also restrained from sliding too quickly down the inclined surfaces A⁶ or before 100 it has had time to straighten up. In other words (see Fig. 4), as the lifting finger C 105 recedes, the matrix lifted thereby will be momentarily suspended by its upper projecting ears upon the tops of shoulders A⁴ and swing from the inclined position X² to the vertical position Y², the relation of said shoulders to the fingers A⁶ being such that 110 the restraining influence of the latter is broken as the matrix reaches the vertical position Y², when it is free to pass straight down the inclined surfaces A⁶ to the pick-up position. It may be noted that the lower 115 edges of the upper guide rails A¹ are notched at A⁸ to provide requisite room for the lower projecting ears as the lifted matrix swings from one position to the other, the forward walls A⁹ of the notches A⁸ 120

serving to prevent the matrix from swinging beyond the vertical position Y². It may also be noted, at this point, that the shoulders A⁵ of the lower rails A² are made 5 considerably shorter than the shoulders A⁴ of the upper rails A¹ so as to be out of the path of the escaping matrices.

In carrying out the present invention, means are also provided to prevent more 10 than one matrix being lifted at a time by the reciprocating finger C, when for any reason, the matrices pile up in the distributor box. In the present instance, such means comprises a separator blade D so formed 15 and arranged that the matrices, although arrested at an inclination, will be separated in the manner required. As in the case of the ordinary separator blade, the forward edge of the blade D is set slightly ahead of 20 the arresting shoulders A³, or a distance determined by the thickness of the thinnest matrix, the matrices of greater thickness being provided with central, vertical cuts 25 or slots x¹ to clear the blade as they are lifted.

Having thus described my invention, its construction, and mode of operation, what I claim and desire to secure by Letters Patent of the United States is as follows:

30 1. In a typographical distributing mechanism, comprising a distributor bar and a set of matrix conveying screws, the combination of a distributor box through which the matrices pass facewise by gravity, means 35 for arresting the matrices at a forward inclination within the box, and means for releasing the arrested matrices one at a time to permit their escape by gravity into position to be picked up by the screws.

40 2. In a typographical distributing mechanism, comprising a distributor bar and a set of matrix conveying screws, the combination of a distributor box through which the matrices pass facewise by gravity, means for 45 arresting the matrices at a forward inclination within the box, means for releasing the arrested matrices one at a time to permit their escape by gravity into position to be picked up by the screws, and inclined surfaces arranged to direct the released matrices to the pick-up position.

50 3. In a typographical distributing mechanism, comprising a distributor bar and a set of matrix conveying screws, the combination of a distributor box through which the matrices pass facewise by gravity, shoulders 55 for arresting the matrices at a forward inclination within the box, a reciprocating finger for lifting the matrices endwise successively above the shoulders so that they 60 may escape by gravity into position to be picked up by the screws, and inclined surfaces leading from the arresting shoulders and down which the released matrices pass 65 to the pick-up position.

4. In a typographical distributing mechanism, comprising a distributor bar and a set of matrix conveying screws, the combination of a distributor box through which the matrices pass facewise by gravity, upper 70 and lower guide rails formed with shoulders arranged to engage the projecting ears of the matrices and arrest the latter at a forward inclination within the box, and a reciprocating finger for lifting the matrices 75 endwise successively above the shoulders so that they may escape by gravity into position to be picked up by the screws.

5. In a typographical distributing mechanism, comprising a distributor bar and a set of matrix conveying screws, the combination of a distributor box through which the matrices pass facewise by gravity, upper and lower guide rails formed with shoulders arranged to engage the projecting ears of the 80 matrices and arrest the latter at a forward inclination within the box, and a reciprocating finger for lifting the matrices endwise successively above the shoulders so that they may escape by gravity into position to 85 be picked up by the screws, the said guide rails being also provided with inclined surfaces leading from the arresting shoulders and down which the released matrices pass 90 to the pick-up position.

6. In a typographical distributing mechanism, comprising a distributor bar and a set of matrix conveying screws, the combination of a distributor box through which the matrices pass facewise by gravity, shoulders 100 for arresting the matrices at a forward inclination within the box, and a reciprocating finger arranged to lift the arrested matrices endwise successively in their own plane above said shoulders so that they may 105 escape by gravity into position to be picked up by the screws.

7. In a typographical distributing mechanism, comprising a distributor bar and a set of matrix conveying screws, the combination of a distributor box through which the matrices pass by gravity, shoulders for arresting the matrices at an inclination within the box, a reciprocating finger for lifting the matrices successively above the shoulders 110 so that they may escape by gravity into position to be picked up by the screws, and a separator blade arranged to cooperate with the arrested matrices so as to prevent more than one matrix being lifted at a time.

8. In a typographical distributing mechanism, comprising a distributor bar and a set of matrix conveying screws, the combination of a distributor box through which the matrices pass facewise by gravity, means for 120 arresting the matrices at a forward inclination within the box, means for releasing the arrested matrices one at a time to permit their escape by gravity into position to be picked up by the screws, and means co- 125

operating with the released matrices to aid them in assuming an upright position before reaching the pick-up position.

9. In a typographical distributing mechanism, comprising a distributor bar and a set of matrix conveying screws, the combination of a distributor box through which the matrices pass by gravity, shoulders for arresting the matrices at an inclination within the box, a reciprocating finger for lifting the matrices successively above the shoulders so that they may escape by gravity into position to be picked up by the screws, inclined surfaces leading from the arresting shoulders and down which the released matrices pass to the pick-up position, and fingers arranged to cooperate with the projecting ears of the lifted matrices to aid them in assuming an upright position in descending the inclined surfaces.

10. In a typographical distributing mechanism, comprising a distributor bar and a set of matrix conveying screws, the combination of a distributor box through which the matrices pass by gravity, upper and lower guide rails formed with shoulders for arresting the matrices at an inclination within the box, and a reciprocating finger for lifting the matrices successively above the shoulders, the arresting shoulders of the upper rails being longer than those of the lower rails for the purpose described.

11. In a typographical distributing mechanism, comprising a distributor bar and a set of matrix conveying screws, the combination of a distributor box through which the matrices pass facewise by gravity, and means for arresting the matrices at a forward inclination within the box and for releasing the arrested matrices one at a time to permit their escape by gravity into position to be picked up by the screws.

12. In a typographical distributing mechanism, the combination of a distributor bar, a set of matrix conveying screws, guide means along which the matrices pass by gravity to the screws, said guide means being adapted to support a plurality of matrices in facewise contact, and means for arresting the matrices at an inclination at a point in advance of the screws and for releasing the arrested matrices one at a time to permit their escape by gravity into position to be picked up by the screws.

13. In a typographical distributing mechanism, the combination of a distributor bar, a set of matrix conveying screws, guide rails along which the matrices pass facewise by gravity to the screws, shoulders for arresting the matrices at a forward inclination upon said rails at a point in advance of but closely adjacent the screws, and a reciprocating finger for lifting the matrices endwise successively above the shoulders so that they may escape by gravity into position to be picked up by the screws.

14. In a typographical distributing mechanism, the combination of a distributor bar, a set of matrix conveying screws, guide rails along which the matrices pass facewise by gravity to the screws, shoulders for arresting the matrices at a forward inclination upon said rails at a point in advance of but closely adjacent the screws, a reciprocating finger for lifting the matrices endwise successively above the shoulders so that they may escape by gravity into position to be picked up by the screws, and inclined surfaces leading from the arresting shoulders and upon which the released matrices pass to the pick-up position.

In testimony whereof, I have affixed my signature hereto.

DAVID S. KENNEDY.
